UNITED STATES PATENT OFFICE.

JENS THEODOR SUHR SCHOUBOE, OF HOLTE, DENMARK.

MECHANISM FOR EXTRACTING AND EJECTING SPENT CARTRIDGE-CASES IN RECOIL-GUNS.

No. 828,977.

Specification of Letters Patent.

Patented Aug. 21, 1906.

Application filed August 7, 1905. Serial No. 273,088.

To all whom it may concern:

Be it known that I, JENS THEODOR SUHR SCHOUBOE, a subject of the King of Denmark, residing at Holte, Denmark, have invented 5 new and useful Improvements in Mechanism for Extracting and Ejecting Spent Cartridge-Cases in Recoil-Guns and the Like, of which the following is a specification.

The invention relates to improvements in 10 mechanism for extracting and ejecting cartridge-shells in recoil-guns and the like.

The improved ejecting mechanism comprises three principal elements—an ejector, a restoring-lever therefor carried by a convenient recoiling part of the gun, and a stationary cam-block, with which the said restoring-lever and ejector coöperate in ejecting the spent shell.

The invention is illustrated in the accompanying drawings, applied to an automatic loader provided with a recoiling barrel, the restoring-lever and ejector being connected with the barrel in a manner to participate in the recoil movement thereof and the cam-block being so disposed with respect to said restoring-lever and ejector that the latter are thrown into relative positions in a manner to engage and eject the spent shell.

In the drawings, Figure 1 is a vertical section of the breech end of a gun, showing the ejecting mechanism and its coöperating parts in the position assumed when the gun is loaded and ready to be fired. Fig. 2 is a similar view showing the position the parts 35 assume during recoil, the shell being partially ejected. Fig. 3 is a similar view showing an extreme position of the parts, the shell being removed and the parts being in position to receive a new cartridge. Fig. 4 is a plan and side elevation of the ejector-restoring lever. Fig. 5 shows side and edge views of the ejector. Fig. 6 is a horizontal section of the breech-casing, showing the cam-blocks with which the restoring-lever 45 and ejector engage in the operation of ejecting a shell.

The ejector consists of a bar 1, provided with a slot 7, adapted to receive a pin 8, carried by a projection 3, formed on the barrel, 50 and around which pin the said ejector swings. Said ejector 1 is provided with a hook 9, which engages the usual groove in the cartridge, the length of the slot 7 providing for the required upward movement of the 55 ejector to effect such engagement. At the bottom the said ejector has a projection 10,

adapted to be engaged and depressed by the restoring-lever 2.

The lever 2 is pivotally mounted upon a pin 11, which, like the pin 8, is secured upon the projection 3. At its forward end the lever 2 is provided with a projection or nose 12 and at its rear with the projection 13, adapted to engage and depress the projection 10, said engagement being effected by the spring 14, interposed between the lever 2 and the barrel. Under the influence of this spring the lever 2 tends to swing the ejector 1 into the position shown in Fig. 1. In this, the firing position, the action of the spring 14 is reinforced by engagement of the nose 12 with the end wall of the casing 4, which latter engagement would in case the spring 14 became displaced or injured serve to insure the restoration of the ejector to the position shown in Fig. 1. The lever 2 carries a lateral projecting pin 15, adapted for engagement with the cam-block, which latter is preferably formed in two pieces 5 and 6, having cam-surfaces disposed in horizontal and inclined planes. The block 5 is recessed between the horizontal portions of the rear wall, forming an abutment 19. When the gun is fired, the breech-block and the barrel recoil and the ejector 1 and lever 2 are carried 85 rearwardly. The lower edge 18 of the ejector 1 engages the inclined surface 16 of the block 5, sliding upwardly thereon, forcing the hook 9 into the groove of the cartridge, the ejector remaining in a vertical position until the pin 15 of the lever 2 strikes the inclined face 17 of the block 6. The projection 10 being freed from pressure of the projection 13, the edge 18 engages the abutment 19 and the ejector is swung rearwardly around the pivot 95 by the continued recoil movement and spent cartridges ejected. It will be understood that simultaneously with the rear movement of the ejector there will be a corresponding upward movement of the breech-block to 100 permit the cartridge to be withdrawn. After the shell is ejected the breech-block again moves downwardly to the position shown in Fig. 3 and, coöperating with the restoring-lever, prevents the ejector from being 105 swung into an upright position until a new cartridge is inserted. During the advance movement the breech-block moves upwardly, closing the cartridge-chamber, and the lever 2 and ejector 1, respectively, are released from the cam-blocks, the ejector actuated by the lever 2, the latter influenced by

the spring 14, advancing to the initial position. (Shown in Fig. 1.)

Having now particularly described and ascertained the nature of my said invention and in what manner the same is to be performed, I declare that what I claim is—

1. A cartridge-ejector for recoil-guns comprising in combination a recoil element, an ejector movably mounted thereon, a restoring-lever movably mounted on said element, and normally engaging the ejector to hold it in a position to engage the shell, and means operating said ejector and lever to eject the shell.
- 15 2. A cartridge-ejector for recoil-guns comprising in combination a recoil element, an ejector movably mounted thereon, a restoring-lever movably mounted on said element, a spring effecting engagement of said lever and the ejector and holding the latter in a position to engage the shell, and means operating the ejector and lever to discharge the shell.
- 25 3. A cartridge-ejector for recoil-guns comprising in combination a recoil element, an ejector movably mounted thereon, a restoring-lever movably mounted on said element, said lever normally engaging the ejector and holding it in a position to engage the shell, and a cam-block having inclined horizontal and abutting surfaces for engagement with said ejector and lever.
- 35 4. A cartridge-ejector for recoil-guns comprising in combination a recoil element, an ejector movably mounted thereon, a restoring-lever movably mounted on said element, a spring effecting engagement of said lever

and ejector and holding the latter in a position to engage the shell, and an ejector-block having inclined horizontal and abutting surfaces for engagement with said ejector and lever.

5. A cartridge-ejector for recoil-guns comprising in combination a recoil element, an ejector loosely pivoted thereon, a restoring-lever pivotally mounted thereon, a spring effecting engagement of the lever and ejector to hold the latter in a position to engage the shell, and a cam-block provided with inclined and horizontal portions and an abutting portion for engagement with said ejector and separate inclined and horizontal portions for engagement with said lever.

6. A cartridge-ejector for recoil-guns comprising in combination a recoil element, an ejector and a restoring element normally in coacting relation and carried by said recoil element, and means throwing said ejector and restoring element successively out of and into coacting relation in ejecting the shell.

7. A cartridge-ejector for recoil-guns comprising in combination a recoil element, an ejector and restoring element carried by said recoil element, and means lying in the path of travel of said ejector and restoring element and operating the same to eject the shell.

In testimony whereof I have signed my name to this specification in the presence of two subscribing witnesses.

JENS THEODOR SUHR SCHOUBOE.
